 The C. W. Zumbiel Company, Cincinnati, Ohio,
 a corporation of Ohio

Application April 27, 1939, Serial No. 270,359

2 Claims. (Cl. 229—32)

This invention relates to collapsible or folding paper or cardboard cartons or boxes, either with a separable or a hinged cover. The body of the box and cover when separable are of a type in which the walls at the corners are in permanent connection. The body, and the separable cover are generally of duplicate construction except that the one is of a dimension to fit or telescope within the other for closing. The walls fold at the corners on diagonal lines of two opposing walls. The present improvement provides for locking or holding the walls in an erected or perpendicular position and in a squared relationship to facilitate loading and closing.

An object of the invention is to interrupt or disturb the continuity of the score or folding lines along which the walls fold to collapse the same from a perpendicular to a flat position in plane or parallel with the base wall, with non-folding segments releasable when folding the walls, and compressively replaceable in erecting the walls to hold the same to a perpendicular position.

Various other features and advantages relating to the corner constructions of the box or carton to facilitate collapsing the walls and to erect and to hold the walls in erected position, all of which will be more fully set forth in the following description of the accompanying drawings in which:

Figure 1 is a plan view of the blank of the body or cover portion of a carton or box;

Figure 2 is a perspective view of a body or cover portion of a carton in a set up or erected position;

Figure 3 is a detailed perspective view of one of the corners, unassembled;

Figure 4 is a perspective view of the box, partly collapsed;

Figure 5 is a perspective view, fully collapsed.

Figure 6 is a perspective view of an end section of a box of modified construction.

Referring to the drawings, Figure 1 discloses a plan which may serve either for the body or cover of the box, as both are of substantially the same construction and pattern, each formed from a sheet of paper board or a like material cut to a definite pattern and scored to provide an intermediate panel 1, representing the bottom of the box or the top when the structure serves as a cover. The intermediate panel 1 is bounded or dimensioned by the score lines 2—2 and 3—3 of rectangular formation. A pair of side walls 4—4, respectively, are integrally joined

with the bottom section at relatively opposite sides thereof and hingedly swing thereon along the score lines 2—2. Correspondingly, a pair of end walls 5—5, are joined with the bottom panel respectively at opposite ends thereof and hingedly swing thereon along the score lines 3—3 to erect the walls to a perpendicular position. Each end wall at its opposite longitudinal ends has a triangular corner flap 6, foldable along a score line 7 to extend at right angles to the wall and overlap the end of an adjoining side wall 4 to which it is preferably permanently secured by an adhesive along two of its margins as indicated in Figures 1 and 2 to leave the intermediate portion of the flap along the diagonal line 2 unsecured. It is obvious, however, that other means may be employed for securing the corner flap to the side wall, and the corner flap may overlap the end of the side wall either on its outer or inner side, preferably as shown, on the outer side for collapsing all of the walls inwardly on the bottom panel.

Each side wall at its opposite longitudinal ends, respectively, is provided with a diagonal score line 8 coinciding with the diagonal edge of a relative corner flap 6, secured to the side wall and laminating the folding end portion of the side wall. The scoring can be comparatively light as the edge of the flap facilitates in the breaking of the wall for folding. The continuity of the score line 8 is interrupted or disturbed by a curved slit 9 extending into the folding portion of the wall, thereby providing an intermediate nonfolding segment which separates or releases from the folding portion of the wall in collapsing the carton by bending the walls inwardly from their perpendicular position to a flat position in plane or parallel with the base panel as illustrated in Figure 4. Upon again erecting the walls the segments are compressively replaceable, rigidly holding the walls to their perpendicular position with the end and side walls squared. A feature of considerable advantage to an erected carton is the operator is relieved from the necessity of spreading the side walls apart while filling.

In lapping the corner flaps 6 upon the outer side walls 4—4, the non-folding segments 9 as the walls are folded or collapsed rest upon the base panel which releases or separates from the wall portions 10 and continue in plane with the intermediate or major portion of the side walls, while the folding portions 10 fold backward upon the side walls. Upon restoring the walls

to their perpendicular position, the segments are pressed into place.

In forming the segments with a very sharp cut, the meeting edges, upon replacing the segments, will frictionally bind together and prevent any bulging of the walls as a result of the folding. The walls, therefore, when erected remain at an absolutely straight position which is of material advantage and benefit in loading the box and applying the cover. The segments being covered on one side by the corner flaps are housed and guarded so that they can not be forced beyond the wall while compressing them in place. The side walls 4—4 at the opposite ends and base are notched as at 12 with an edge of the notch extending along the folding line or extensive thereof. This notching avoids any bulking of the material at the base of the corner or extending the fold to the extreme point at the lower end of the wall, so that the parts are relieved of any strain which would cause tear or injury to the material at the corner in folding.

In the modified form shown in Figure 6, the end walls 5 are provided with the interrupted diagonal fold or score lines 8, and the curved slits 9 which form the non-folding segments corresponding substantially as previously described for the side walls. In this instance the sidewalls are provided with triangular corner flaps or gussets 6 which, however, are disposed upon the inner side of the end walls, instead of the outerside of the sidewalls as in the first instance. The corner flaps or gussets 6 are secured to the end walls at the top margin thereof preferably by staples 11—11 and are dimensioned to enter beyond the interrupted diagonal fold lines 8—8. In collapsing the walls the end walls are pushed inwardly which results in a separation of the nonfolding segments from the folding triangular end portion of the walls, and the corner edges of the segments formed by the slits 9 slide past the corner flaps or gussets 6, which fold in a plane parallel with their rela-

tive side walls, which they underlie in the collapsed position of the box. This action is permissible on account of the loose condition of the corner flaps by being only marginally secured to the top of the end walls.

Having described my invention I claim:

1. A collapsible box formed from a blank having fold lines defining a rectangular base panel, side and end wall panels secured to said base along said fold lines, the end wall panels having at each end thereof an integral right triangular tab having its base defined by the continuation of the fold line of the adjacent side and its hypotenuse extending from the adjacent corner of the base panel, each end of the side panels having a centrally interrupted diagonal fold line defining a folding portion, each fold line terminating at its respective adjacent corner of the base panel, each interrupted portion of each fold line having its adjacent ends connected by a slit extending into said foldable portion, said slits defining non-folding projecting tabs, the foldable portion of each folding portion when in operative position being secured to its adjacent right triangular tab.

2. A collapsible box formed from a blank having fold lines defining a rectangular base panel, side and end wall panels secured to said base along said fold lines, each end of the side panels having a centrally interrupted diagonal fold line defining a folding portion, each fold line terminating at its respective adjacent corner of the base panel, each interrupted portion of each fold line having its adjacent ends connected by a slit extending into said foldable portion, said slits defining non-folding projecting tabs, the end wall panels having a tab at each end thereof, each secured to the foldable portion of an adjoining side wall panel, foldable therewith and in an erected position of the wall panels covering one side of the non-folding tab.

CLIFFORD HOLT KAMP.
